Application May 13, 1940, Serial No. 334,841

2 Claims. (Cl. 113—38)

This invention relates to improvements in presses of the type embodying a crown, a bed and a slide reciprocable toward and away from the bed, and one of the objects of the invention is to provide in a press of this character improved means for guiding the slide in its movement.

In presses of this character as now generally constructed the guiding means for the slide are usually a portion of the uprights and of necessity are limited in height when they are so constructed as they cannot reach beyond the lower surface of the crown.

Furthermore when a hollow frame construction is employed there are certain weaknesses when the gibs are on the hollow uprights.

It is therefore one of the objects of the present invention to provide guiding means for the slide which are located at a considerable distance away from the surface of the slide to which the dies are attached, and in so doing provide guiding means in addition to the usual guiding means. It is well known that the further away the guides can be located from the bottom surface of the slide the more accurate they will be and the parallelism of the slide under off-center pressures will be more easily maintained.

A further object is to provide additional guiding means in the form of gibs that may be readily adjusted and which will not be limited in height.

To the attainment of these ends and the accomplishment of other new and useful objects as will appear, the invention consists in the features of novelty in substantially the construction, combination and arrangement of the several parts hereinafter more fully described and claimed and shown in the accompanying drawings illustrating this invention, and in which

Figure 1 is a view partly in elevation, partly broken away and partly in section of a press constructed in accordance with the principles of this invention.

Figure 2 is a vertical sectional view taken on line 2—2 Figure 1.

Figure 3 is a view on an enlarged scale, partly broken away, and partly in section of one of the adjustable guides or gibs.

Figure 4 is a detail horizontal sectional view taken on line 4—4 Figure 1.

Figure 5 is a horizontal sectional view taken on line 5—5 Figure 6.

Figure 6 is a vertical detail sectional view of the slide.

In the present exemplification of the invention the press is of a sectional construction and con-

sists essentially of a base 10 having a bed 11 upon which rests a bed plate 12.

Rising above the base 10 are hollow uprights 13 and supported by these uprights is a crown 14, these parts being tied or fastened together by means of tie rods 15 to the ends of which may be secured nuts or collars 16.

10 Reciprocable between the uprights 13 is a slide 17, to the bottom face of which may be secured an operating die.

15 The slide may be provided with surfaces 18 which contact and move upon gibs 19 that in turn may be secured in position and upon the uprights 13 by means of suitable fastening bolts 20.

20 In each of the uprights 13 there is provided a space 21 having open sides through which the respective ends or extremities 22 of the slide project and in which space said ends reciprocate.

25 Any suitable means may be provided for reciprocating the slide, such as a shaft 23 journaled in bearings 24 in the base 10 and which shaft extends across the base. This shaft is provided with eccentric portions 25 one being preferably located in alignment with each of the uprights 13, the shaft being rotated in any suitable manner and from any suitable source of power, preferably through the medium of a drive pulley 26 secured thereto.

30 Co-operating with each of the eccentrics 25 is a link or eccentric strap 27, the free end of each of which is provided with a bearing 28 in each of which bearings an eccentric 29 operates. The eccentrics 29 are connected with a shaft 30 which is journaled in suitable bearings 31 in the slide 35 17.

Upon rotation of the shaft 23 a reciprocatory movement will be imparted to the slide 17 through the medium of the various eccentrics and eccentric straps.

40 In order to vary the path of movement of the slide 17 with respect to the base 10 while the extent of reciprocation of the slide remains constant, the shaft 30 may be rotated so as to rotate the eccentrics 29 and thereby vary their position within the respective bearings 28. This may be accomplished in any suitable manner such as by means of a worm gear 32 secured to the shaft 30 and with which worm gear a worm 33 meshes, the worm 33 being carried by a shaft 34 journaled in bearings 35 in the slide.

45 The end of the shaft 34 may be angular in cross-section, as at 36, for the reception of a crank or other implement through the medium of which the shaft 34 may be rotated. Upon rotation of this shaft it will be manifest that the

worm 33 meshing with the gear 32 will rotate the shaft 30.

Projecting above the slide 17 are extensions 37 which pass through openings 38 in the crown 14 and these extensions 37 may be of any desired length and size. Supported by the crown and at opposite ends of the openings 38 are brackets 39 being secured in position in any desired or suitable manner, such as by means of fastening bolts 40. These brackets are provided with inclined surfaces 41a preferably arranged at the bottom of a channel 40. A gib 41 having an inclined surface 42 fits within the channel 40 and the inclined surface 42 of the gib contacts the inclined surface 41a of the channel 40, the sides 15 of the channel serving as a means for assisting in preventing lateral displacement of the gibs 41. The gibs are adjustably held in position by means of a screw 43 which is threaded through a flange 44 of the gib and is also threaded, as at 45, into the bracket 39.

By rotating the screw 43 it will be manifest that the gib 41 will be raised or lowered with respect to the bracket 39 and if desired and in order to hold the gib in its adjusted position nuts 25 or collars 46 may be employed.

As an additional means for holding the gib in its adjusted position a screw 47 may be employed. This screw is threaded through the bracket 39 and contacts the edge of the gib 41, the screw 30 being adjustable by means of an angularly shaped head 48.

One of these gibs 41 is arranged adjacent each of the edges of the extensions 37 on the slide. The gibs 41 contact and move against a wear plate 49 carried by the extensions of the slide and secured in position in any suitable manner. These wear plates 49 are preferably recessed into the respective edges of the extensions 37, as at 50.

With this improved construction it will be manifest that the gibs 41 are not only adjustable to compensate wear, but being located at a considerable distance from the die carrying surface of the slide 17 there will be provided guiding means for the slide separate from and in addition to the guiding means or gibs 19 which are carried by the uprights beneath the crown, thereby resulting in the provision of additional guiding means for the slide which is not only located as

far as possible from the surface of the slide to which the dies are fastened but which will not be limited in height.

While the preferred form of the invention is herein shown and described, it is to be understood that various changes may be made in the details of construction and in the combination and arrangement of the several parts, within the scope of the claims, without departing from the spirit of this invention.

What is claimed as new is:

1. In a press embodying a crown and a slide reciprocable between guides located below the crown, the combination of a rigid extension connected to each end of the slide and projecting for a substantial distance above the slide, each of said extensions being of a substantial width in a direction transverse to the longitudinal dimension of the slide, each extension passing freely through an opening in the crown, and cooperating pairs of guide members individual to said extensions and between the members of each of which pairs one of said extensions reciprocates, the last said guide members being rigid and mounted upon the crown and projecting above the top thereof, each of the lateral edges of each of said extensions having a free sliding engagement with one of the last said guide members.

2. In a press embodying a crown and a slide reciprocable between guides located below the crown, the combination of a rigid extension connected to each end of the slide and projecting for a substantial distance above the slide, each of said extensions being of a substantial width in a direction transverse to the longitudinal dimension of the slide, each extension passing freely through an opening in the crown, and cooperating pairs of guide members individual to said extensions and between the members of each of which pairs one of said extensions reciprocates, the last said guide members being rigid and mounted upon the crown and projecting above the top thereof, each of the lateral edges of each of said extensions having a free sliding engagement with one of the last said guide members, each of said extensions filling the space between the respective members of the pairs of guides.

RUDOLPH W. GLASNER.
